INVENTOR

EDWARD NAUER

BY *Arthur L. Sibley*
ATTY.

UNITED STATES PATENT OFFICE.

EDWARD NAUER, OF SAN FRANCISCO, CALIFORNIA.

GAS HEATER.

Application filed March 22, 1927. Serial No. 177,328.

My invention relates to improvements in heaters arranged to be set over a burner or a gas plate or the like for heating a room.

The primary object of the present invention is to provide an improved heater which may be removably placed over a gas burner to provide a large heat radiating area whereby a room may be quickly and economically heated.

10 10 A further object is to provide an improved device of the character described arranged to insure a complete combustion of the gas before the products of combustion pass from the heater into the room.

15 15 Another object is to provide an improved construction which can be economically manufactured, and which will be neat and attractive in its appearance.

20 20 A still further object is to provide, as a new article of manufacture, an improved heating device which can be readily placed over any convenient gas burner to obtain a quick or temporary heating of a room.

25 25 I accomplish these and other objects by means of the improved device disclosed in the drawings forming a part of the present application wherein like characters of references are used to designate similar parts throughout the specification and drawings, 30 and in which,

35 35 Fig. 1 is a vertical section through my improved heater, and Fig. 2 is a broken plan view of the heater, portions being broken away and shown in section to illustrate the construction and arrangement.

40 40 Referring to the drawings, my improved heater will be seen to consist of an outer shell 1, having converging sides and closed across the top by means of a top plate 2. A plurality of openings 3 are formed in the lower portions of the sides of the shell 1.

45 45 A bottom member 4 is secured within the bottom of the shell 1, said member 4 being provided with a flanged edge 6 arranged to nest within the bottom edge of the shell 1 and to hold the bottom member in spaced relation to said bottom edge. A plurality of openings 7 are formed in the bottom member 4.

50 50 An inner shell 8 is secured upon the upper side of the bottom member 4, said shell converging upwardly. The shell 8 is closed across the top and has a plurality of openings 9 formed around the sides. A flange 11 is preferably formed upon the lower edge

of the shell 8 whereby said shell may be secured upon the bottom member 4.

A baffle member 12 is mounted within the heater between the outer and inner shells 1 and 8, respectively, said member 12 having its sides converging to form a relatively small opening at the top slightly below the top plate 2. The lower edge of the member 12 is nested between the shell 1 and the flange 6.

60 65 A frame 14 is fitted around the lower edge of the shell 1, said member preferably being cast and provided with a flange 16 to which the shell 1, the member 12, and the flange 6 are firmly clamped in proximate relation by means of suitable securing members 17.

70 75 The heater is preferably made in rectangular form, the outer shell 1, the bottom 4, the inner shell 8, and the baffle member 12 each being formed in frusto-pyramidal form. Each of these members are formed from suitable sheet metal. The top 2 is crimped onto the top of the shell 1 and the shell 8 is bolted or otherwise secured upon the bottom member 4. The members 1, 12, and 4 are then nested and secured together as above explained. Handles 18 are preferably secured upon opposite sides of the shell 1 whereby the heater may be lifted and moved.

80 85 In operation, the heater is placed above any suitable burner not shown, as the burners of a gas plate or gas stove. The flame from such burner is directed against the raised bottom portion 4, and the products of combustion pass through the openings 7 and into the inner shell 8. From the inner shell, the products of combustion, and air drawn upwardly therewith, pass through the openings 9 and thence upwardly through the open upper end of the baffle member 12.

90 95 The air and combustion gas must then descend around the outside of the member 12 and pass outwardly through the openings 3. This causes the gas and air to follow a tortuous path whereby a complete combustion is caused before the products pass outwardly from the heater into the room. At the same time, the gas and air passing through the heater are retained for sufficient time to insure a thorough drying of the air and gas. This prevents the escape of objectionable fumes into the room and insures a dry atmosphere. The bottom member 4 and the inner shell 8 are heated to a very high degree, and heat is transmitted to the baffle and to the

outer shell, thereby obtaining a relatively large area from which the heat may radiate, and at the same time, the outer shell is protected from the extreme heat present directly over the heater, thereby permitting a neat and attractive appearance to be maintained.

The device is particularly useful for heating a room quickly, as in the early morning before an apartment has been heated. The 10 device is also useful for the temporary heating of an apartment, as when a regular source of heat has been turned off or is inoperative. The large heating area and the complete combustion and drying of the 15 fuel permits it to be used over any open burner to obtain a rapid heating of the room with only a small consumption of fuel.

Having thus described my invention what I claim as new and desire to secure by Letters 20 Patent is,

1. An article of manufacture, a gas heater comprising an outer shell closed at its upper end and having openings formed around the

lower portion of its sides; a baffle member nested within the outer shell and open at the 25 top thereof; and an apertured bottom shell nested within the baffle member to protect said outer shell and baffle from direct exposure to a burner below the apertured bottom shell.

2. An article of manufacture, a gas heater comprising an outer shell closed at its upper end and having openings formed around the lower portion of its sides; a baffle member nested within the outer shell and open at the 35 top thereof; and an apertured bottom shell nested within the baffle member to protect said outer shell and baffle from direct exposure to a burner below the apertured bottom shell; and an apertured inner shell having a closed top and mounted upon the bottom member to diffuse heat within the baffle member.

In witness whereof I hereunto set my signature.

EDWARD NAUER.
